UNITED STATES PATENT OFFICE.

JULIUS A. BIDWELL, OF STURGIS, MICHIGAN.

IMPROVEMENT IN BASES FOR ARTIFICIAL TEETH.

Specification forming part of Letters Patent No. **38,091**, dated April 7, 1863.

To all whom it may concern:

Be it known that I, JULIUS A. BIDWELL, of Sturgis, in the county of St. Joseph and State of Michigan, have invented a new and useful Improvement in bases of Artificial Teeth, by means of which improvement a more perfect and ready adaptation to the mouth is secured, and thereby the comfort of the wearer promoted.

The nature of my invention consists in providing the bases of artificial teeth with flexible air-chambers, secured nearly upon the central portion of the base, and made more elastic or flexible than the base itself, whether made of the same or different materials.

To enable others skilled in the art to make and use my invention, I will proceed to describe its construction and advantages.

I construct the base to which the artificial teeth are secured of any of the known forms or materials. I prefer to construct it of vulcanized caoutchouc, though I do not wish to be confined to any specific material.

In the drawings, A represents the base to which the teeth are attached; B the central air-chamber, made more flexible or elastic than

the base A, and perfectly united with it. The advantage of this construction is obvious. It is well known in practice that it is difficult to exclude the atmosphere from between the roof of the mouth and the upper portion of the base A, by exhausting it with the tongue. Now, by my invention the manipulation of the thumb or finger may be more advantageously employed, and thus a better vacuum secured, as the base by this means adheres with more tenacity (the atmospheric pressure being greater) to the roof of the mouth. At the same time the solidity and strength of the base itself remains unimpaired.

What I claim as new, and desire to secure by Letters Patent, is—

The employment, upon the bases of artificial teeth, (being a part of the base itself,) of a flexible air-chamber or intervening medium for the purposes and uses expressed, and in the manner substantially as set forth.

JULIUS A. BIDWELL.
